(57) **CLAIM**

I claim the ornamental design for a toilet utensils holder, as shown and described.

DESCRIPTION

FIG. 1 is a top perspective view of my ship design for a toilet utensils holder.

FIG. 2 is a right side view sectional view in elevation of the design shown in FIG. 1, the left side view being a mirror image.

FIG. 3 is a top plan view of my design.

FIG. 4 is a side view in elevation of my design.

FIG. 5 is a rear view in elevation of my design; and,
FIG. 6 is a bottom plan view of my design.

The parts shown in broken lines do not comprise a part of the design.
